Ch. Farren Attorney

UNITED STATES PATENT OFFICE.

HENRY W. WOLF, OF STELLA, NEBRASKA.

GRAIN-CAR DOOR.

Application filed December 5, 1921. Serial No. 520,009.

To all whom it may concern:

Be it known that I, HENRY W. WOLF, a citizen of the United States, residing at Stella, in the county of Richardson and 5 State of Nebraska, have invented certain new and useful Improvements in Grain-Car Doors, of which the following is a specification.

This invention relates to grain car doors.

10 An important object of the invention is to provide a pair of complementary door sections adapted when open to permit the ends of a grain car to be filled and to permit the center of the car to be conveniently filled 15 without spilling the grain when the doors are in the closed position.

A further object of the invention is to provide a center post adapted to support the meeting edges of the doors when the car is 20 filled, said center post being adapted to be removed from its normal position when the doors are open and when it is desired to fill the ends of the car without obstructing the door opening.

25 A further object of the invention is to provide manually operated means carried by the center post for effecting the initial opening movements of the doors when it is desired to unload the car.

30 Other objects and advantages of the invention will be apparent during the course of the following description.

In the drawings I have shown one embodiment of the invention. In this showing,

35 Figure 1 is a side elevation of a portion of a grain car showing the invention applied thereto;

Figure 2 is a similar view looking from the inside of the car;

40 Figure 3 is a section taken on line 3—3 of Figure 1;

Figure 4 is a section taken on line 4—4 of Figure 1, showing the center post in inoperative position, and with the door open, the 45 lever being omitted;

Figure 5 is a section taken on line 5—5 of Figure 1, the lever being omitted.

Figure 6 is a detail perspective of the center post and associated elements, and,

50 Figure 7 is a detail section taken on line 7—7 of Figure 2.

In the drawings, wherein for the purpose of illustration is shown a preferred embodiment of my invention, the numeral 10 designates

55 a box car or grain car having the usual door opening 11 and sliding door 12'. The door opening 11 is provided with the usual framing 12.

In carrying out my invention I provide a pair of complementary door sections 13 preferably formed of sheet iron or steel and these door sections are pivoted to the framing 12 by means of bolts 14 passing through the lower outer corners of the doors. As clearly shown, the inner edges of the doors 60 are adapted to overlap when the doors are in the closed position. The doors are provided near their inner and upper edges with openings 13' for a purpose to be described. The numeral 15 designates a pair of guide 65 bars having their upper ends secured to the framing as at 16 and their lower ends secured to the floor of the car in any suitable manner. As shown in Figures 4 and 5, the guide bars 16 are positioned slightly inwardly of the outer edges of the doors 13 to prevent the door from swinging inwardly of 70 the car. It will be apparent that the doors may be swung outwardly from the center post to assume the position shown in dotted 75 lines in Figure 2. I provide a pair of keepers 18 on opposite sides of the door opening to receive the edges of the doors when they are in the opened position.

As shown, outward movement of the overlapped edges of the door is prevented by 80 means of a center post designated as a whole by the numeral 19. This center post comprises a long lower section 20 terminating at its lower end in a foot 21 adapted to be received within a socket 22 formed in the floor 85 of the car. As shown, socket 22 has a vertical outer face, while the inner portion is beveled or curved upwardly to the floor level for a purpose to be described. The numeral 90 23 designates an upper or short section of the center post pivotally connected at its lower end to the upper end of the section 20 by means of a pin 24 riveted at its ends upon washers 24'. As shown, the pin 24 is offset 95 outwardly with respect to the center post and the adjacent edges of the sections of the center post terminate in contacting shoulders 25 and 26 to prevent the center post from bending outwardly. The upper 100 end of the section 23 terminates in an eye 27 which connects with a screw eye 28 carried by the wall of a car to form a universal 105

hinge connection. As shown in Figure 3, when the door sections are opened the hinge portion of the center post may be swung inwardly and the foot 21 drawn upwardly 5 along the curved portion of the slot until the foot of the center post is free from the slot whereupon the entire center post may be swung upwardly longitudinally of the car to assume the position shown in the dotted lines 10 of Figure 2. A bracket 29 is provided to receive and support the center post when in the elevated position.

Pivottally connected to the center post upon a bolt 30 disposed above the door sections, is a retaining member 31, preferably a semicircular in form and provided with a handle 32. When the doors are closed, the retaining member may be turned to the position shown in Figure 2 with one end resting 20 upon one door and the other end resting upon both the overlapped ends of the door. It will be apparent that since the pivot 30 is intermediate the ends of the retaining member 31, the doors cannot be opened until the 25 retaining member is revolved through substantially one-half a revolution.

As shown in Figure 3 the bolt 30 extends entirely through the center post and is provided upon its outer end with an eye 33 30 which carries a link 34 on the lower end of which is a ring 35. The numeral 36 designates a lever connected near its inner end with the ring 35. It will be obvious that the lever 36 is permanently fastened to the center post but is free to be moved in any direction.

The operation of the device is as follows:

When it is desired to load a car with grain or the like, the doors 13 are swung outwardly 40 longitudinally of the car to assume the position shown in the dotted lines in Figure 2. The center post is then hinged inwardly as shown in the dotted lines of Figure 3 and then swung upwardly into the bracket 29 as 45 shown by the dotted lines in Figure 2. The entire door opening is then unobstructed so that the ends of the car may be readily filled. When the grain reaches a position 50 in the car near the door, the center post is released from the bracket 29 and swung downwardly into its normal position, and the doors swung inwardly and retained in position by means of the retaining member 31. Grain or the like may then be introduced 55 through the spaces above the doors 13 until the car is filled. When it is desired to unload the car, the operator lifts the outer end of the lever 36 and inserts the inner end of the lever within first one and then the other of the openings 13' and moves the handle 36 downwardly thus prying the door 60 upwardly a substantial distance from the floor of the car as indicated in the dotted lines in Fig. 1, whereby the bottoms of the 65 doors may be grasped by the hands of the

operator and swung to the fully open position.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. The combination with a car body having a door opening therein, the floor of said car body being provided with a recess adjacent the center of the door opening, of a center post hinged at its upper end to said car body, the lower end of said post being disposed within said recess, said post being provided intermediate its ends with a hinge, 80 a pair of complementary door sections hinged to the car body and adapted to cover the lower portion of the door opening, said door sections having their inner edges disposed adjacent said post, and single means carried 85 by said post for forcing both of said doors to and maintaining them in closed position.

2. The combination with a car body having a door opening therein, the floor of said car body being provided with a recess adjacent the center of the door opening, of a center post universally hinged at its upper end to said car body, the lower end of said post being adapted to be disposed within said recess, said post being provided intermediate its ends with a hinge, a pair of complementary door sections hinged to the car body to swing upwardly and outwardly with respect to the door opening and adapted to cover the lower portion of the door opening, 105 said door sections having their inner edges overlapping and disposed adjacent said post, and a retaining member pivoted intermediate its ends to said post, one end of said member being adapted to rest upon the upper edge of one door to one side of said post, the other end of said member being adapted to rest upon the upper edges of the overlapped portions of said doors.

3. The combination with a car body having a door opening therein, said car body being provided with a recess adjacent the center of the door opening, of a center post secured to said car body, to swing upwardly and outwardly with respect to the door opening a pair of complementary door sections hinged to the car body and adapted to cover the lower portion of the door opening, said door sections having their inner edges overlapping and disposed adjacent said post, and a retaining member pivoted intermediate its ends to said post, said retaining member being substantially semicircular in form, one end being adapted to act as a cam to contact 120 with the overlapped edges of the door where- 125 130

by to force them to closed position, the other end being adapted to rest upon the upper edge of one of said doors to one side of said post.

- 5 4. The combination with a car body having a door opening therein, the floor of said car being provided with a recess adjacent the center of the door opening, of a center post hinged at its upper end to said car body, the lower end of said post being adapted to be disposed within said recess, said post being provided intermediate its ends with a hinge, a pair of complementary door sections hinged to the car body and adapted
- 10

to cover the lower portion of the door opening, a bolt mounted in said post, means carried by the inner end of said bolt for forcing said doors to and maintaining them in closed position, and means carried by the outer end of said bolt for effecting the initial opening movement of said doors.

In testimony whereof I affix my signature in presence of two witnesses.

HENRY W. WOLF.
